UNITED STATES PATENT OFFICE.

WILLIAM L. GUMPRECHT, OF NEW YORK, N. Y., ASSIGNOR TO JOHN THOMAS
UNDERWOOD, OF BROOKLYN, NEW YORK.

TYPE-WRITING MACHINE.

Specification of Letters Patent. Patented June 23, 1914.

1,101,070.

Application filed March 19, 1913. Serial No. 755,328.

To all whom it may concern:

Be it known that I, WILLIAM L. GUMPRECHT, a subject of the King of Great Britain, residing in Brooklyn, in the county of 5 Kings, city and State of New York, have invented certain new and useful Improvements in Type-Writing Machines, of which the following is a specification:

My invention relates to mechanism in a 10 front-strike typewriting machine, by which a ribbon is vibrated to cover and uncover the printing point at every type stroke, and is of special value when used with a ribbon comprising a plurality of color bands or stripes. 15 In bichrome ribbons, the color bands are narrow, and do not permit of much latitude in the position of the ribbon over the printing point. The rapid movement of the vibrator is apt to result in an overthrow of the 20 ribbon.

An object of the present invention is to provide simple stop mechanism which forms positive means to prevent overthrow of the ribbon vibrator.

25 The invention is illustrated in connection with ribbon-vibrating mechanism of a front-strike Underwood typewriting machine. The type bars actuate a universal bar which carries an actuator for a ribbon vibrating lever.

30 The lever has pins at different distances from its fulcrum, each adapted to engage a vertical slot in the actuator, the latter being shiftable to connect either pin with the actuator to vary the throw of the ribbon. A 35 stop device on the vibrator lever contacts with a dog or stop on the universal bar each time a type is brought to printing position, thereby positively limiting the upward throw of the vibrator at all of the four printing 40 positions of the latter. The stop device comprises four stops or shoulders, positioned to correspond to the four different positions of the lever relatively to the universal bar when a type bar is in printing position, these positions depending on whether the platen is in 45 upper or lower case position, and whether the vibrator is adjusted for the upper or lower color band of the ribbon. The stop on the universal bar is pivoted to prevent 50 the stops from accidentally interlocking.

Other objects of the invention will appear hereinafter.

In the accompanying drawings, Figure 1 is a sectional elevation view of an Under-

wood typewriting machine with my invention applied thereto. Fig. 2 is a perspective view of the ribbon-vibrating mechanisms. Figs. 3 to 6 are sectional elevation views of the same. Fig. 3 shows a type bar in printing position with the upper color band of 55 the ribbon over the printing point. Fig. 4 shows the lower color band in printing position. Figs. 5 and 6 show the platen shifted to upper case position, and the upper and lower color bands respectively over the 60 printing point. Fig. 7 is an enlarged detail view of the vibrator lever.

Keys 1 are connected to levers 2 which operate type bars 3 mounted on a pivot rod 4 and adapted to be swung upward to printing 70 position in front of the platen 5. The platen is mounted in a frame 6 pivoted at 7 to a carriage 8 having a sliding connection with a rail 9 fixed to the machine frame 10. The platen frame carries a roller 11 which 75 runs on a shift rail 12 shiftable up and down by means of a bell crank 13 operated by a shift lever 14, to the front end of which is attached a shift key 15. The feed of the carriage in letter-space direction is controlled by a rack 16, pinion 17, escapement wheel 18, and escapement dogs 19 operated and controlled as usual by a universal bar 20. The universal bar 20 has a pivotal connection 21 with rock arms 22 fulcrumed at 23. 80 A ribbon vibrator 24 has a pivotal connection 25 with the forward end of a vibrator lever 26 pivoted at 27 to a bracket 28 fixed to the shift rail 12. Pins 29 and 30, extending from opposite sides of the vibrator lever 26 and at different distances from its pivot 27 to vary the throw of the vibrator, are adapted to enter respectively vertical slots 31 and 32 in forwardly extending wings formed on 85 the actuator 33. The actuator has a slidable connection with an upright plate 34 secured to the universal bar 20.

The invention is particularly adapted for use with a bichrome ribbon comprising upper and lower color strips or zones 35 and 100 36, which may be black and red respectively, or any other desired colors. The throw of the vibrator or its amplitude of vibration is controlled by shift keys 37 and 38 on a lever 39 at the forward end of a rock shaft 40, to 105 the rear end of which is secured an arm 41 pivoted to a link 42 connected to the actuator 33. When the key 37 is depressed the

actuator is moved to the right to project the pin 29 into the slot 31. With the parts in this position, the lower color band will be brought to printing position when the type bars are actuated. When the actuator is shifted to the left by depressing the key 38, the pin 30, which is farther from the fulcrum 27 than the pin 29, enters the slot 32 and causes a shorter throw of the vibrator, so that the upper color band is brought into operative position. Each type bar is formed with a heel 44 in position to move the universal bar rearwardly as the type bar moves to printing position, and thereby actuate the ribbon vibrator and the escapement mechanism in the usual manner.

In order to positively limit the upward movement of the ribbon vibrator, and thus prevent overthrow, coöperating stop devices 45 and 46 are carried by the vibrator lever 26 and the universal bar respectively, or these devices 45 and 46 may be carried respectively by the universal bar and vibrator lever. The stop device 45 is formed with four stops or shoulders *a*, *b*, *c*, *d*, adapted to engage the stop 46 which is shown as a dog connected by a pivot 47 to a bracket 48 on the universal bar. The dog 46 is pivoted, for a purpose which will appear hereinafter, and is normally held against a stop pin 51 by means of a spring 49.

When the key 38 is in depressed position so that the upper color band will be effective, and a type bar is operated to the position shown in Fig. 3, the universal bar 20 is thereby moved rearward and swings the vibrator lever 26 upward so that the shoulder or stop *a* contacts with the dog 46, thereby forming a positive stop for the vibrator and preventing the ribbon from being carried above its normal position. Without this stop any play at the pivot 27 or lateral play between the pin 30 and slot 32 would permit the ribbon to be moved upward beyond its normal position owing to its momentum when the parts are operated very rapidly, so that a portion of the printed character would receive its impression through the lower color band. It will also be observed that the stop on the vibrator lever serves to limit the movement of the universal bar 20. Without such stop, the universal bar is sometimes moved backward by its momentum beyond the point to which it is positively operated by the type bar, this also resulting in an overthrow of the ribbon, but when the stops are in engagement any force tending to move the universal bar backward reacts through the slot and pin connection to produce a counteracting forward pressure on the universal bar.

If the key 37 is depressed so that the actuator 33 engages the pin 29, as shown in Fig. 4, the throw of the vibrator will be in-

creased sufficiently to bring the lower color band over the printing point when a type bar is actuated. This increased throw of the vibrator lever 26 brings the shoulder or stop *b* into position to engage the dog 46. As the throw of the lever 26 in this instance is greater for a given movement of the universal bar than in the Fig. 3 adjustment, the first stop *a* is carried above the position shown in Fig. 3 before the stop 46 has moved back far enough to engage it.

Referring to Fig. 5, when the shift key has been operated to lift the platen to upper case position, the vibrator lever is carried up with it, and the actuator being adjusted for the upper color band, as in Fig. 3, the third stop or shoulder *c* is brought into position to engage the dog 46. If the actuator 33 is shifted for the lower color band, and the platen is in upper case position (Fig. 6), the fourth stop *d* will be brought against the dog 46 when a type bar is actuated.

The purpose of pivoting the dog 46, see Fig. 7, is as follows: In rapid operation, when the platen has been shifted to upper case position, the shift key is sometimes released permitting the platen to drop or commence its downward movement before the type bar has had time to move away from the platen. If the dog 46 were rigid with the universal bar, such operation would permit the shoulder 50 between the stops *c* and *d* to rest on the dog and thereby prevent the return of the platen to lower case position. In other words, the dog 46 bearing against the shoulder 50 would hold both the vibrator lever and the platen up. By yieldingly mounting the dog 46 as shown, it can readily swing down to permit the stop to slip past so that the parts can return to normal position. The spring 49 is weak enough to permit such operation. The same result may be obtained by pivoting the stop 45, in which case the stop 46 could be rigid with its support.

Variations may be resorted to within the scope of the invention, and portions of the improvements may be used without others.

Having thus described my invention, I claim:

1. In a typewriting machine, the combination with a ribbon vibrator having a stop, of a universal bar having a counter-stop to engage the first stop to prevent overthrow of the ribbon, and a shiftable device to vary the printing position of the ribbon and prevent the engagement of said stops.

2. In a typewriting machine, the combination with a ribbon vibrator having a stop, of a universal bar having a counter-stop to engage the first stop to prevent overthrow of the ribbon, a shiftable device to vary the printing position of the ribbon and prevent the engagement of said stops, and a second

- stop engageable by said counter-stop to prevent overthrow of the ribbon after the operation of said shiftable device.
3. The combination with a ribbon vibrating mechanism, of stops, a counter-stop, a shiftable device for varying the printing position of the ribbon, and means controlled by said shiftable device for determining which of said stops shall coöperate with said counter-stop. 70
4. In a typewriting machine, a ribbon vibrating mechanism including members movable at each type stroke and which assume different relationships to each other at the completion of the printing stroke when the ribbon occupies different positions over the printing point, and coöperating stops upon said members brought together in different relative positions for arresting the ribbon vibrator. 75
5. In a typewriting machine, the combination with a ribbon vibrator or holder, of key-controlled mechanism for vibrating the same, said key controlled mechanism including a member which has a uniform movement and one which has a variable movement to vary the position occupied by the ribbon over the printing point, and stop devices coöperating with said members for preventing overthrow of the ribbon beyond either of its printing positions; said stop devices including one which is effective when said variable member has relatively slow movement, and ineffective when it has relatively quick movement, and also including another stop which is ineffective in the first instance and effective in the second. 80
6. In a typewriting machine, the combination with a ribbon vibrator or holder, of key controlled mechanism for vibrating the same, said key-controlled mechanism including both a member which has a uniform movement and also a member which has a variable movement to vary the position occupied by the ribbon over the printing point; and stop devices including a series of stops on one of said members and a counter-stop on the other of said members; said series including one which engages the counter-stop when the ribbon-vibrating member is moving at relatively slow speed, but which misses said counter-stop when said ribbon-vibrating member is moving at relatively high speed, and also including a second stop which engages said counter-stop when said ribbon vibrating member is moving at relatively high speed. 85
7. In a typewriting machine, the combination with a ribbon vibrator or holder, of means for vibrating the same at the type strokes, said vibrating means including two members relatively movable; a shiftable device for varying the relative speed of said members for the purpose of varying the printing position of the ribbon, and co- 90
- operating stops on said members to prevent overthrow of the ribbon vibrator in its different printing positions; said stops including both a counter-stop on one of said members and also stops on another of said members arranged to selectively engage said counter-stop, according to the relative speeds for which said members are set by said shiftable device. 95
8. The combination with a ribbon-vibrator or holder, of vibrating means including a reciprocating member and a lever vibrated thereby; a shiftable device for varying the relative speed of said lever and reciprocating member, and coöperating stops on said lever and reciprocating member to prevent overthrow of the ribbon vibrator; said stops including both a counter-stop and stops arranged to alternatively engage said counter-stop, according to the relative speeds for which said lever and reciprocating member are set by said shiftable device. 100
9. In a typewriting machine having a case-shift mechanism, the combination with a ribbon vibrator or holder, of key-controlled mechanism for vibrating the same, said key-controlled mechanism connected to the case-shift mechanism to be shifted therewith, and including both a member which has a uniform movement and also a member which has a variable movement to vary the position occupied by the ribbon over the printing point in each of the positions to which the ribbon mechanism is shifted by the case-shift mechanism; and stop devices including both two sets of stops and a counter-stop device; one of said sets arranged to come into play at one position of the case-shift mechanism, and the other of said sets arranged to come into play at the other position of said case-shift mechanism; each of said sets including a stop which engages the counter-stop device when the ribbon-vibrating member is moving at relatively slow speed, but which misses said counter-stop device when said ribbon-vibrating member is moving at relatively high speed, and also including a second stop which engages said counter-stop device when said ribbon-vibrating member is moving at relatively high speed. 105
10. In a typewriting machine having a case-shift mechanism, the combination with a ribbon-vibrating mechanism connected to said case-shift mechanism, and a ribbon-shift mechanism for bringing different widthwise portions of the ribbon into play, of four stops, and a counter-stop arranged to arrest the ribbon-vibrating mechanism at the conclusion of the printing stroke with the ribbon in two different positions over the printing point, in each position of the case-shift mechanism. 110
11. In a typewriting machine, the combination of a universal bar, ribbon vibrating 125

mechanism actuated thereby, and coöperating stops on said bar and mechanism limiting the relative movement of said parts.

12. In a typewriting machine, the combination with a universal bar, of a ribbon vibrator, a stop on the vibrator, and a stop on the universal bar in the path of said first-named stop, said stops brought together at each type stroke to stop the movement of the 10 vibrator and universal bar.

13. In a typewriting machine, the combination of a type bar, a universal bar actuated thereby, a ribbon vibrator, and stops on said universal bar and vibrator in position 15 to be brought together and stop the relative movement of the universal bar and vibrator when the type bar is in printing position.

14. In a typewriting machine, the combination with a type bar, of a universal bar 20 operated thereby, a vibrator lever operated by the universal bar, a stop carried by said lever, and a coöperating stop on the universal bar to limit the movement of the vibrator lever and universal bar.

15. In a typewriting machine, the combination with a type bar and a universal bar 25 operated thereby, of a ribbon vibrator operated by the universal bar, and coöperating stops moved by the universal bar and vibrator for into and out of contact and stopping the movement of the said lever and universal bar.

16. In a typewriting machine, the combination with a universal bar, of a ribbon vibrator actuated thereby, and stops moved by the universal bar and vibrator into abutting contact to stop the universal bar and vibrator and thereby prevent overthrow of the 35 vibrator.

17. In a typewriting machine, the combination with a front-strike type bar, a universal bar moved rearward by the type bar, a ribbon vibrator lever, connections between 40 said lever and the universal bar for operating the lever, a stop on said lever carried forward during the printing stroke, and a coöperating stop on the universal bar.

18. In a typewriting machine, the combination with a platen shiftable to upper and 45 lower case positions, of a vibrator lever shiftable up and down with the platen, a universal bar, an operating connection between said bar and lever, a stop on said bar, and coöperating stops on the vibrator lever adapted to coöperate respectively with said 55 first-named stop when the platen is in lower and upper case positions.

19. In a front-strike typewriting machine, the combination with a platen shiftable to 60 upper and lower case positions, of a ribbon vibrator comprising a vibrator lever shiftable with the platen, a universal bar, an operating connection between said bar and lever, a stop on said bar, a stop on the lever 65 to engage the stop on said bar when the lat-

ter is operated with the platen in lower case position, and an additional stop on the lever to engage the stop on said bar when the platen is in upper case position.

20. In a typewriting machine, the combination with a ribbon vibrator, of a universal bar, operating connections between said bar and vibrator, means for changing said connections to vary the throw of the vibrator, a stop on the universal bar, and stops on the vibrator having positions corresponding to the throw of the vibrator.

21. In a typewriting machine, the combination with a universal bar, of a vibrator, operating connections between said bar and vibrator, means to vary the throw of the vibrator, type bars to actuate the universal bar, a stop on the universal bar, a coöperating stop carried by the vibrator to contact with the first stop when a type bar is in printing position, and another stop carried by the vibrator in position to contact with the first-named stop when a type bar is in printing position when said connections have been shifted to vary the throw of the 90 vibrator.

22. In a typewriting machine, the combination with a platen shiftable to upper and lower case positions, front-strike type-bars, a universal bar operated by the type bars, a ribbon vibrator lever shiftable up and down with the platen, operating connections between the vibrator lever and the universal bar, means to shift said connections to vary the throw of the vibrator lever, a stop carried by the universal bar, and a series of coöperating stops carried by the vibrator lever and positioned to correspond to the actuated positions of the vibrator lever resulting from the shifting of the lever up and down with the platen and the variation in the throw of the lever.

23. In a typewriting machine, the combination with a type bar, of a universal bar actuated thereby, a stop pivoted to the universal bar, a ribbon vibrator actuated by the universal bar, and a stop carried thereby and coöperating with said pivoted stop.

24. In a typewriting machine, the combination with a platen shiftable up and down, of a ribbon vibrator shiftable with the platen, a universal bar, a stop carried thereby, a series of coöperating stops on the vibrator, and means to permit the stops to pass each other when the platen returns from shifted position.

25. In a typewriting machine, the combination with a type bar, of a universal bar actuated thereby, a ribbon vibrator actuated by the universal bar, and a stop carried by 125 said vibrator to limit the movement of the universal bar.

26. In a typewriting machine, the combination with a type bar, of a universal bar actuated thereby, a ribbon vibrator, and co- 130

- operating stops carried by the universal bar and vibrator and operative to limit the throw of the vibrator and the movement of the universal bar.
27. In a typewriting machine, the combination with type bars, of a universal bar operated thereby, a ribbon vibrator, operating connections between the vibrator and the universal bar, and stops carried by the universal bar and vibrator and brought together at the completion of a type stroke, and thereby positively stopping both the universal bar and vibrator.
28. In a typewriting machine, the combination of a universal bar, a ribbon vibrator lever, a connection between the lever and universal bar at one side of the lever fulcrum, a stop carried by the lever on the opposite side of its fulcrum, and a coöperating stop on the universal bar.
29. In a typewriting machine, the combination with front-strike type bars, of a universal bar moved rearwardly by the type bars when the latter are brought to printing position, a ribbon vibrator comprising a lever having an arm extending above its pivot, an operating connection between said arm and the universal bar, said lever having a depending arm, a stop carried thereby, and a stop on the universal bar in the path of the first-named stop.
30. In a typewriting machine, the combination with type bars, of a universal bar moved rearwardly by the operation of the type bars, ribbon-vibrating mechanism operated by the universal bar and comprising a member moved forwardly during the rearward movement of the universal bar, and co-
- operating stops on said member and universal bar.
31. In a typewriting machine having a case shift mechanism, the combination with ribbon vibrating mechanism carried by the case shift mechanism and movable up and down therewith, stops on said vibrating mechanism, and a counter-stop arranged to engage said first-named stops and arrest the ribbon vibrating mechanism when the case shift mechanism is in either position.
32. In a typewriting machine, the combination of a ribbon vibrator, a universal bar operated at each type stroke, connections between said bar and the ribbon vibrator for vibrating the latter at each type stroke, and stops carried by the universal bar and said vibrator, each stop moving toward the other during a type stroke and brought into engagement when the ribbon is over the printing point.
33. In a typewriting machine, the combination with a case shift mechanism, of a ribbon vibrator carried thereby and movable up and down therewith, a universal bar operated at each type stroke, connections between said bar and the ribbon vibrator for vibrating the latter at each type stroke, and stops carried by the universal bar and said vibrator, each stop moving toward the other during a type stroke and brought into engagement when the ribbon is over the printing point.
